UNITED STATES PATENT OFFICE.

HERBERT CORRAL, OF HELENSBURGH, SCOTLAND, ASSIGNOR TO THE SINGER MANUFACTURING COMPANY, OF ELIZABETH, NEW JERSEY, A CORPORATION OF NEW JERSEY.

DUPLEX SEAM FOR SEWED ARTICLES.

Application filed August 6, 1921. Serial No. 490,316.

(GRANTED UNDER THE PROVISIONS OF THE ACT OF MARCH 3, 1921, 41 STAT. L., 1313.)

To all whom it may concern:

Be it known that I, HERBERT CORRAL, a subject of the King of the United Kingdom of Great Britain and Ireland, and residing at Helensburgh, Dumbartonshire, Scotland, have invented a certain new and useful Improvement in Duplex Seams for Sewed Articles (for which I have filed applications in the following countries: Great Britain,

10 filed Dec. 5, 1913, Patent No. 28,012, dated Dec. 5, 1913; Germany, filed Nov. 28, 1914, and July 8, 1920; Germany, G. M., filed Nov. 28, 1914, Patent No. 640,100, dated Nov. 29, 1914, and filed July 8, 1920; Belgium, filed Jan. 5, 1920; France, filed Dec. 15, 1919, Patent No. 507,475, dated Dec. 16, 1919; Italy, filed Dec. 26, 1919, Patent No. 518/27, dated Dec. 31, 1919; Poland, filed April 7, 1920; Spain, filed Dec. 31, 1919,

20 Patent No. 72,031, dated May 6, 1920; Sweden, filed Dec. 24, 1919; and Switzerland, filed Jan. 26, 1920, Patent No. 87,186, dated Jan. 26, 1920), of which the following is a specification.

25 This invention relates to a duplex seam for uniting the abutted edges of fabric sections and aims at the production of a flat ornamental seam suitable for hosiery, for example.

30 The duplex seam according to the invention comprises two separate stitch-formations one of which is superposed upon the other and each of which embraces the abutted edges of the fabric sections. The first stitch-formation may be in the form of a retaining seam constituted by two needle-threads which are formed into parallel rows of needle-loops and serve to bind to one side of the abutted fabric sections

35 at least one sinuously laid covering or ornamental thread extending from row to row and each of which needle-thread loops is enchainued in its own row on the other side of the fabric sections with a looper cross-

40 thread extending from row to row. The superposed seam overlies the first seam along a relatively narrow zone embracing the abutted edges of fabric and is preferably made narrower than and disposed within 45 the borders of the first seam. The second seam preferably includes two needle-threads which are formed into rows of needle-loops extending parallel to the rows of needle-loops of the first mentioned seam. The

needle-loops of the superposed seam are each 55 enchainued in its own row on the second mentioned side of the fabric with a looper cross-thread extending from row to row.

The superposed seam serves to bind to the fabric the covering thread and the looper 60 thread of the first formed seam and cooperates with the first seam to doubly cover the meeting edges of fabric sections.

In the accompanying drawings which illustrate the invention by way of example 65 Figs. 1 and 2 are diagrammatic views showing, respectively, the upper and lower sides of two fabric sections joined by a duplex seam.

c and *d* represent a pair of needle threads 70 spaced apart a distance representing, in the particular embodiment of the invention illustrated, the total width of the seam. The spaced pairs of opposed needle loops extending through the fabric sections *a* and *b* on opposite sides of the abutted edges are joined and anchored on the lower face of the fabric by a lower or looper cross-thread *e* extending across the edges to be joined. On the upper side of the fabric 80 sections a covering thread or cross-thread *f* is secured by means of the needle-threads *c* and *d*.

g and *h* represent needle-threads, preferably relatively closely spaced, the spaced 85 pairs of needle loops of which are joined and anchored by a looper thread *j* which crosses and recrosses the line of division between the fabric sections.

The threads *g*, *h* and *j* serve to maintain 90 the threads in close contact with the fabric.

It will be seen that the separate stitch-formations are superposed along a narrow zone which is disposed centrally of the duplex seam and embraces the abutted edges 95 of fabric, which edges are thus doubly covered.

I claim:

1. A duplex seam for sewed articles comprising two fabric sections, a first seam for 100 joining the abutted edges of said fabric sections, said first seam including spaced pairs of opposed needle loops, a looper cross thread joining and anchoring said pairs of opposed needle loops on one face of the fabric, a cross thread joining the opposed pairs of needle loops on the other face of the fabric, and a superposed seam disposed within 105

- the borders of the first seam and including
needle and looper threads at least one of
which crosses and recrosses the line of division
between the fabric sections.
5. 2. A duplex seam for sewed articles comprising two fabric sections, a first seam for joining the abutted edges of said fabric sections, said first seam including spaced pairs of opposed needle loops, a looper cross
10 thread joining and anchoring said pairs of opposed needle loops on one face of the fabric, a cross thread joining the opposed pairs of needle loops on the other face of the fabric, and a superposed seam disposed
15 within the borders of the first seam and including spaced pairs of opposed needle loops located on opposite sides of said meeting edges, and a looper cross thread joining and anchoring said opposed needle loops on one
20 face of the fabric.
3. A duplex seam for sewed articles comprising two fabric sections having a pair of separately formed seams for covering the proximate edges of said fabric sections, each
25 of said seams comprising two needle threads formed at intervals into loops passing through the respective fabric sections and a looper cross thread concatenated with said needle-loops and extending back and forth
30 across said edges, one of said looper cross threads overlying and serving to bind down the other looper cross thread.
4. A duplex seam for sewed articles comprising fabric sections having their edges
35 to be joined arranged in parallel relation, a first seam including spaced pairs of opposed needle-loops, a looper cross thread joining and anchoring said pairs of opposed needle-loops on the under face of the fabric, and
40 a covering thread joining the opposed pairs of needle-loops on the upper face of the fabric, and a second seam formed over the first seam and including spaced pairs of opposed needle-loops and a second looper cross-
45 thread joining and anchoring said pairs of needle-loops on the under face of the fabric, both of said looper threads extending across the edges of material to be joined.
5. A seam for sewed articles comprising
50 fabric sections having their edges abutted,

a series of stitches connecting said sections and comprising spaced rows of opposed needle thread loops respectively extending through the fabric sections on opposite sides of the abutted edges, a looper thread
55 concatenated with said needle thread loops and forming a line of single chain loops on one side of the meeting edges of the fabric sections, and a separate series of stitches connecting and anchoring said fabric sections against being separated by a strain transverse of the meeting edges of the fabric sections, said separate series of stitches including spaced rows of opposed needle thread loops and a looper thread concatenated therewith, said last-mentioned looper thread being formed into a series of loops
60 respectively concatenated with each pair of the last-mentioned needle-thread-loops after passing through the needle thread loops of a previous pair and extending over and covering the first-mentioned looper thread.

6. An ornamental seam for uniting two fabrics comprising two needle threads disposed in parallel stitch rows, a lower thread
65 extending from stitch-row to stitch-row and concatenated on the under side of the fabrics with both needle threads, each in its own stitch row, a covering thread extending from stitch-row to stitch-row on the upper side of the fabrics, two additional needle threads disposed in stitch rows parallel with the first mentioned stitch rows, said additional needle threads serving to bind said covering thread to the fabrics,
70 and a second lower thread extending from stitch-row to stitch-row of the second mentioned stitch rows and concatenated on the under side of the fabrics with both said additional needle threads each in its own
75 stitch-row and adapted to bind said first mentioned lower thread to the fabrics.

In testimony whereof I have signed my name to this specification in the presence of two subscribing witnesses.

HERBERT CORRALL.
